UNITED STATES PATENT OFFICE.

ERHARD ALLEN, OF DAYTON, OHIO, ASSIGNOR TO THE DAYTON DISPLAY FIXTURE COMPANY, OF DAYTON, OHIO, A CORPORATION OF OHIO.

DISPLAY STAND.

Application filed September 22, 1924. Serial No. 738,981.

To all whom it may concern:

Be it known that I, ERHARD ALLEN, a citizen of the United States, residing at Dayton, in the county of Montgomery and State of Ohio, have invented certain new and useful Improvements in Display Stands, of which the following is a specification.

This invention relates to new and useful improvements in display stands, and more particularly to a shelf fixture for displaying electrical goods, hardware and like goods in an attractive manner.

It is the principal object of the invention to provide a display stand, which is preferably made of sheet metal, for displaying hardware, electrical goods, camera supplies and like articles in an attractive manner, without permitting the vertical parts of the fixture, such as the legs, standards or other members, to obtrude upon the vision of the observer and thereby destroy the proper exhibition of the goods themselves. Articles supported by the fixture appear to float, as it were, in the air, and thereby to stand out to view without the observer being conscious of any parts of it save its horizontal ones.

It is a further object of the invention to provide a display fixture which has plain, simple lines, wide open spaces and an ornamental dignity and balance, with no obtruding portions such as numerous legs and other vertical parts make.

It is another object of the invention to provide a display stand which adds its own qualities to objects such as lamps, vases and like articles which it is adapted to exhibit, so that both the fixture and the objects displayed by it may blend together in an attractive whole.

It is still another object of the invention to provide a fixture which may be economically manufactured in sections from sheet metal, and thereafter easily assembled to form the complete display unit.

In the accompanying drawings, Figure 1 is a perspective view of the shelf fixture assembled and ready for use. Figure 2 is a plan view of the bottom shelf partly broken away to show the construction of the truck frame. Figure 3 is a sectional view taken on the line 3—3 of Figure 2, showing the form of the truck frame construction. Figure 4 is a sectional view taken on the line

4—4 of Figure 5, showing the construction of a shelf cross brace. Figure 5 is a side elevational view, partly in section, of the display stand, showing the construction of the longitudinal shelf braces and the angle uprights secured to the truck frame. Figure 6 is a cross sectional view taken through the edge of a shelf, showing the marginal side member that is bent over it. Figure 7 is a cross sectional view taken through one of the angle uprights. And Figure 8 is a cross sectional view taken on the line 8—8 of Figure 3, showing the countersunk, telescopic construction of the bolt holes in the angle uprights and the shelf bracing members secured thereto.

Referring to the accompanying drawings for a detailed description of the form of embodiment of the invention illustrated therein, the numerals 1, 1 designate two side, base channel members which are preferably constructed of sheet steel by suitable dies or other forming apparatus. Each channel member, as shown in Figure 5, is formed at each end with an upwardly inclined lower edge portion 2 to give it a bracing property while providing foot room.

These side channel members 1, 1 are connected together in vertical parallelism by end members 3, 3 constructed of sheet steel, each one of which is formed along its top edge with an outwardly projecting horizontal flange 4, and at its lower edge with an inwardly projecting flange 5. (See Figures 2 and 5.) The end members 3, 3 also have end flanges 6, 6 which are secured by rivets 7 to the inner surfaces of the channel members 1, 1 between their top flanges 8 and bottom flanges 9.

Formed at each corner of the frame which the side members 1, 1 and the end members 3, 3 thus make, through their bottom flanges 9 and 5 respectively, are registering holes through which the threaded stem 10 of a caster 11 projects. However, this stem first projects through a hole in the base part of a side bracket arm 12, so that when a nut 13 is screwed on the stem 10 of the caster, this arm 12 will not only be firmly secured to the bottom flange 9 of its respective side channel member 1, but the bottom flange 5 of the end member 3, as well as a caster 11, will be firmly secured to said flange 9. (See

Figures 3 and 5.) It is thus possible to easily and securely assemble the side, end, bracket and caster members to provide a strong supporting base for the shelf structure soon to be described.

Secured to the middle inner portion of each end member 3 is the bottom part of an angle upright member 14 which is preferably constructed of a piece of sheet steel in the shape 10 shown in Figure 7, by bending its middle portion upon itself and then turning its facing sides to form two end flanges 15, 15 that project away from each other in the same vertical plane. Countersunk holes 15 formed in each end member 3, telescope into countersunk holes formed in the flanges 15, 15 of its respective upright 14, to receive screw bolts 16 to the outer ends of which nuts 17 and lock washers 17^a are applied. 20 These nuts 17 are the means of drawing the uprights 14, 14 tightly against their respective end members 3 for the purpose of assisting the telescopic projections containing the bolt holes in firmly securing said uprights to these end members. (See Figures 25 3 and 8.)

Referring to Figures 2 and 6, the numeral 19 designates a shelf which is also preferably constructed of sheet steel, and which 30 has formed in its central portion, near each end, a T slot 20 that enables it to be slipped over the two angle uprights 14, 14 for support upon the side channel members 1, 1. Each shelf 19 is formed along each of its 35 outer edges with a downwardly depending flange 21 that fits into the U-shaped space between the lower side flanges of a marginal member 22 that is formed from sheet steel or like material. This member is bent 40 upon itself to form a U-shaped space or pocket between its side flanges, one of which extends upwardly above the shelf 19, and is then bent downwardly against itself to enter said U-shaped space, forming 45 around the shelf a marginal side flange which projects a sufficient distance above the shelf to provide a bead 23.

Through holes in the flange 21 of the shelf 19 and the side member 22, and registering 50 holes formed in the arm brackets 12, bolts 24 are passed. To the latter nuts 25 are applied for the purpose of securing the flanged shelf to the arm brackets so that it may be firmly supported upon the side channel 55 members 1, 1. (See Figure 3.)

Secured by screw bolts 16 in the manner illustrated in Figure 8, to the U portions of the angle uprights 14, 14, is a longitudinal middle shelf brace 26 having a flanged top. 60 Attached to the end flanges 15, 15 of the uprights 14 a short distance above the longitudinal middle member 18, are shelf cross braces 27, 27. These cross braces are formed with countersunk holes which telescope into countersunk holes in the flanges 65

15, 15 of the uprights 14, to receive screw bolts 16 to which nuts 17 are applied for the purpose of drawing said braces tightly against the uprights in the same manner that the latter are secured to the end members 3. 70

Each cross brace 27 is formed along its upper edge with an outwardly turned flange 28, while its bottom edges incline upwardly from its wide middle portion to 75 outwardly turned right-angled ears 30 containing suitable bolt holes. Adapted to be placed upon the longitudinal brace 26 and the cross braces 27, 27, is a metal shelf 31 similar to the shelf 19. The T slots in this 80 shelf 31 permit it to be slipped over the uprights 14, 14 until it rests upon the longitudinal brace 26 and the cross braces 27, 27, whereupon the marginal sides of the shelf are secured to the ears 30 of the cross braces 85 by the screw bolts 16. (See Figures 4 and 5.)

Above the shelf 31 longitudinal braces 26 and their cooperating pairs of cross braces 27, 27 are connected to the uprights 14, 14 90 at suitable intervals by screw bolts 16. The braces 26 and 27 immediately above the shelf 31 support a shelf 32 constructed like the latter, but of less area, while the top braces 26 and 27 support a similar shelf 33 95 of less area than the one below. Any number of shelves may be so supported by the uprights 14, 14 and the longitudinal braces 26 and cross braces 27, 27 secured to them, to provide a complete fixture which is not 100 only attractive and sturdy in appearance, but which is durable and easily assembled from a knock-down form for immediate use.

Having described my invention, I claim:

1. A display stand comprising a truck 105 frame, uprights secured thereto, a longitudinal brace and co-operating cross braces secured at intervals to said uprights, shelves having side flanges, mounted upon said longitudinal braces and their co-operating 110 cross braces, and concealed means formed on the ends of the cross braces to which the side flanges on the shelves are secured.

2. A display stand comprising a truck 115 frame, uprights secured thereto, a longitudinal brace and co-operating cross braces secured at intervals to said uprights, said cross braces having right-angled ears formed on their ends, shelves mounted on said longitudinal braces and their co-operating 120 cross braces, and side flanges on the shelves secured to said ears and extending below the latter to conceal them from view.

3. A display stand comprising a pair of 125 base channel side members, flanged end members secured between the latter, bracket arms projecting upwardly from below the bottom flanges on the side and the end members, the lower parts of said bracket arms and the bottom flanges on the side and end 130

members having registering holes, casters having threaded stems projecting upwardly through said registering holes, nuts applied to the threaded stems of said casters and a bottom shelf resting upon said side and end members and secured to said brackets.

4. A display stand comprising a pair of base channel side members, flanged end members secured between the latter, 10 bracket arms projecting upwardly from below the bottom flanges on the side and end members, the lower parts of said bracket arms and the bottom flanges on the side and end members having registering holes, 15 casters having threaded stems projecting through said registering holes, casters having threaded stems projecting upwardly through said registering holes, nuts applied to the threaded stems of the casters, a bottom shelf resting upon said side and end

members, and marginal sides on said shelf secured to said brackets.

5. A display stand comprising a pair of base channel members, flanged end members secured between the latter, and having 25 countersunk holes in their middle portions, a plurality of shelves, a pair of angle uprights for supporting said shelves, and having countersunk holes in their bottom portions into which the countersunk holes in 30 the end members project, and fastening means adapted to be passed through said registering countersunk holes for the purpose specified.

In testimony whereof I have hereunto set my hand this 15th day of September, 1924.

ERHARD ALLEN.

Witness:

HOWARD S. SMITH.
